UNITED STATES PATENT OFFICE.

LOUIS ISAAC BECKWITH, OF BOSTON, MASSACHUSETTS.

SEPARABLE JOINT.

1,321,802.

Specification of Letters Patent. Patented Nov. 18, 1919.

Application filed January 17, 1917. Serial No. 142,782.

To all whom it may concern:

Be it known that I, LOUIS ISAAC BECKWITH, a citizen of the United States, and resident of Boston, in the county of Suffolk and State of Massachusetts, have invented new and useful Improvements in Separable Joints, of which the following is a specification.

This invention relates to separable joints for knock-down structures, such as metal meat-racks and other racks designed for heavy loads, where rigidity and the prevention of play between the parts are important requisites.

15 In the accompanying drawings which illustrate the invention,

Figure 1 is a plan view of a corner joint illustrating one embodiment of the invention;

20 Fig. 2 is a section on line 2—2 of Fig. 1; Fig. 3 is a section on line 3—3 of Fig. 1; Fig. 4 is a front elevation of the structure shown in Fig. 1;

25 Fig. 5 is a plan view of a modification; Fig. 6 is a section on line 6—6 of Fig. 5; and

Fig. 7 is an elevation of the structure shown in Fig. 5 viewed in the direction of the arrow 7.

30 The separable joints illustrated in the drawings are designed especially for use in frames comprising essentially vertical uprights and horizontal shelves supported between the uprights. One of the uprights,

35 which are preferably made of metal rod or piping, is shown at 10. The lower joint member is formed in a bracket 11, which is preferably a metal casting, and is mounted to slide on the upright 10. The bracket 11

40 is secured in the desired position of adjustment by a set screw 12. The lower joint member comprises a concave curved wall 13 and a post 14, spaced one from the other. The surface of the wall 13 and the opposed

45 surface 15 of the post preferably converge from the top downwardly, thus forming a downwardly tapering socket, open at the top. In the form shown in Figs. 1 to 4, a lower joint member of the construction above de-

50 scribed is provided at each end of the bracket 11 for supporting a corner of a shelf at each side of the upright 10.

The upper joint member is in the form of a casting 16, having a curved web 17, taper-

ing from the top downwardly, and fitting 55 into the space between the curved wall 13 and the post 14. The casting 16 is provided with a pair of laterally extending wings 18 of angular cross section, to which are riveted or otherwise secured angle bars 19 60 forming the frame of the shelf.

To insure the rigidity of the assembled joint and prevent relative angular rotation of the two members on the curved surfaces of the wall 13 and web 17, I provide mutually engaging abutments, herein shown as shoulders 21 formed on projections 20 of the upper member, engaging shoulders 22 on the lower member. Each pair of coöperating abutments, 21, 22, is located beyond the region of the mutually fitting curves of the wall 13 and the web 17, and is disposed transversely of said engaging joint surfaces. Any tendency of the two joint members to rotate or slip angularly on the curved surfaces is effectively checked by said abutments.

The modification shown in Figs. 5 to 7 comprises a bracket 11^a for a single joint member instead of two, and possesses certain 80 advantages in the saving of space in that the upright 10 is brought within the rectangle defined by the shelf. The bracket 11^a instead of having a concave curved wall has a convex curved wall 13^a; and the upper joint member 16^a has a correspondingly curved web 17^a fitting into the space between the wall 13^a and the post 14. The tapered form of the web and socket, and the angle wings 18 and shelf frame 19 may be the same as 90 before. The abutments for preventing relative angular rotation of the two members are shown at 21^a on the projection 20^a of the upper member, and at 22^a on the lower member. Said coöperating abutments, as 95 before, are located beyond the region of the mutually engaging curved walls of the joint members.

In either form the taper of the web and the socket, of the upper and lower members 100 respectively, not only draws the mutually engaging curved surfaces tightly together, but also draws the abutments into close engagement thus insuring the rigidity of the assembled joint.

105 I claim:

A separable joint for knock-down frames comprising a lower member having a curved

wall and a post spaced one from the other, and an upper member having a curved web fitting said curved wall and extending into the space between the wall and post of the lower member, the upper member and the lower member each having a pair of vertically disposed coöperating abutments lo-

cated beyond the region of and extending outwardly from said mutually fitting curves.

10

Signed by me at Boston, this 4th day of January, 1917.

LOUIS ISAAC BECKWITH.
